UNITED STATES PATENT OFFICE.

DELMAR D. PINKHAM, OF LONGVIEW, TEXAS.

SCREEN.

No. 835,636.

Specification of Letters Patent.

Patented Nov. 13, 1906.

Application filed May 18, 1906. Serial No. 317,561.

To all whom it may concern:

Be it known that I, DELMAR D. PINKHAM, a citizen of the United States, residing at Longview, in the county of Gregg and State of Texas, have invented a new and useful Screen, of which the following is a specification.

This invention relates more particularly to window and door screens in which metal frames are employed.

One of the principal objects is to provide an exceedingly simple frame structure that can be shipped and sold in knockdown condition and readily assembled by the purchaser or user.

A further object is to provide a frame which will constitute an effective clamp for the wire-netting without the danger of cutting such netting.

20 A still further object is to provide supporting or guiding means for the frame, which is adjustable in order that it may be accommodated to any inaccuracies in the window-frame to which the screen is applied.

25 One of the embodiments of the invention is disclosed in the accompanying drawings, wherein—

Figure 1 is a front elevation of the screen, showing the same in place upon a window-frame. Fig. 2 is a horizontal sectional view through the same. Fig. 3 is a detail perspective view, on an enlarged scale, through one of the lower corners of the frame. Fig. 4 is a sectional view on the line 4-4 of Fig. 3. Fig. 35 5 is a detail perspective view of one of the corner-pieces.

Similar reference-numerals designate corresponding parts in all the figures of the drawings.

40 In the embodiment illustrated side rails 6 are employed that are composed of sheet metal, each side rail consisting of a body portion having an outer angularly-disposed marginal flange 7, the flange being doubled upon itself to provide leaves 8. An inner marginal flange 9 is also provided, which flange is doubled, as shown, and is bent back upon the body, the doubled free edge being rounded, as shown at 10. The various side rails are 45 similarly shaped and may be of different lengths in order that different sized frames may be constructed for different windows.

The side rails are connected by corner-pieces 11, which consist of angularly-disposed arms 12, the outer sides of which have 55 outstanding longitudinally-disposed flanges 13. These flanges have their adjacent ends preferably beveled and separated, as shown at 14. In order to prevent the corner-pieces bending at the juncture of the arms, they are 60 preferably reinforced by strengthening-beads 15. These beads may or may not be employed, as desired. The arms 12 overlap the ends of the side rails. The inner margins of said arms are clamped between the inner 65 flanges 9 and the body-strip 6 of said rails. The outer flanges 13 are clamped between the leaves 8 of the outer flanges 7 of the side rails, as clearly shown in Figs. 3 and 4.

Wire-netting 16 extends across the space 70 defined by the frame formed as above, and this netting has its margins doubled about the rounded edges 10 of the inner flanges 9 of the side rails, the edges of the netting being clamped between said flanges 9 and the body-75 strips 6 of said side rails, as clearly shown in Fig. 2.

The structure as thus far described can be employed either for door or window screens. When employed for the latter purpose, 80 guides are provided in which the screens slide. These guides are made of sheet metal, and each consists of a rear wall 17 and a front wall 18, connected to one edge and overlying said rear wall, being disposed substantially 85 parallel thereto. An outstanding retaining-wall 19 projects from the opposite edge of the rear wall 17 in angular relation to said rear wall and the front wall being spaced from the latter, thereby forming a slot 20 and an 90 inclosed guideway 21. Two guides are employed which are secured to opposite sides of the window-frame by fasteners 22, preferably in the form of screws, that pass through the rear and front walls 17 and 18 and adjustably connecting the same, so that by setting the screws in or out the distance between the walls may be varied. The screen is mounted on these guides by having the outer flanges 7 of the upright side rails engaged between the walls 17 and 18 at one side of the fasteners 22, as shown in Fig. 2, the side rails projecting through the slots 20. 95 100

It will be apparent that the parts forming

the frame can be readily and cheaply manufactured, that they may be shipped and sold in knockdown condition, and can be put together by the purchaser. In this structure, the guideways being adjustable, inaccuracies in the window-frame can be readily provided for. The screen-frame has a number of decided advantages. In the first place it will be seen that the arrangement described is very simple, and different parts are made to perform a plurality of functions. Thus the flanges 7 and 9 of the side rails strengthen said rails, so as to prevent their bending. They constitute clamps for the corner-pieces, and, furthermore, the outer flange acts as a guide, while the inner flange secures the netting. This inner flange, moreover, being doubled, as shown, provides a rounded bearing for the netting, and thereby eliminates the danger of cutting said netting.

From the foregoing it is thought that the construction, operation, and many advantages of the herein-described invention will be apparent to those skilled in the art without further description, and it will be understood that various changes in the size, shape, proportion, and minor details of construction may be resorted to without departing from the spirit or sacrificing any of the advantages of the invention.

Having thus fully described my invention, what I claim as new, and desire to secure by Letters Patent, is—

1. In a screen, the combination with a guide comprising a rear wall, and a front wall carried by one edge of the same and spaced therefrom, of a fastening device adjustably passing through the walls and constituting means for holding them different distances apart, and a screen-frame having a side rail provided with an offset marginal flange that engages between the walls of the guide at one side of the fastening device.

2. In a screen, the combination with a guide comprising a rear wall, and a front wall carried by one edge of the rear wall and spaced therefrom, and an angularly-disposed retaining-wall carried by the outer edge of the rear wall and spaced from the free edge of the front wall, forming a slot, of fastening devices adjustably passing through the front and rear walls and constituting means for holding them different distances apart, and a screen-frame having a side rail that projects into the slot of the guide and has an offset marginal flange that engages between the front and rear walls of the guide at one side of the fastening devices.

3. In a screen, a frame comprising side rails, each having a body portion with inner and outer outstanding marginal flanges disposed on one side of the body portion, and a corner-piece comprising angularly-disposed

arms that fit flat against the ends of the body portion and have their inner and outer side margins clamped between the inner and outer marginal flanges, one of said flanges of each rail being disposed flat against that face of the associated arm which is not in contact with the body portion.

4. In a screen, a frame comprising side rails, each being composed of body-strips having inner and outer marginal flanges on one side, the inner flange being bent back upon the body-strip, the outer flange being disposed in outstanding relation and comprising doubled leaves, and a corner-piece comprising angularly-disposed arms that overlap the ends of the rails, the inner margins of the arms being clamped between the inner flanges and body-strips of the rails, the outer margins of the said arms having outstanding flanges that are clamped between the leaves of the outer flanges of the rails.

5. In a screen, the combination with angularly-disposed side rails, including body portions, of corner-pieces associated with the adjacent ends of the side rails, netting extending across the space between the rails, and flanges carried by the body portions of the rails, said flanges having portions that clamp the corner-pieces against the body portions of the rails, and portions that clamp the netting against said body portions of the rails.

6. In a screen, the combination with angularly-disposed side rails, comprising metal strips having body portions and integral inner marginal flanges, of corner-pieces associated with the adjacent ends of the rails and clamped against the body portions by portions of said marginal flanges, and netting extending across the space between the rails and clamped against the body portions by portions of said marginal flanges.

7. In a screen, the combination with upright rails and upper and lower rails, said rails having outer outstanding marginal flanges comprising doubled leaves, of corner-pieces connecting the rails and comprising angular arms having offset outer flanges clamped between the leaves of the rail-flanges, and guides in which the flanges of the upright rails are slidably mounted.

8. In a screen, the combination with upright rails and upper and lower rails, said rails comprising body-strips having outer outstanding marginal flanges comprising doubled leaves, and inner marginal flanges that are doubled and bent back upon the strips, of corner-pieces connecting the rails and comprising angular arms having offset outer flanges clamped between the leaves of the outer rail-flanges, the inner margins of said flanges being clamped between the inner marginal flanges of the rails and the bodies of said rails, netting clamped between the inner

marginal flanges of the rails and the bodies of | my own I have hereto affixed my signature
said rails, said netting being doubled about | in the presence of two witnesses.
the doubled edges of the inner flanges, and |
guides in which the outer flanges of the outer |
5 rails are slidably mounted, said guides com- |
prising spaced adjustably-connected walls.
In testimony that I claim the foregoing as |
my own I have hereto affixed my signature
in the presence of two witnesses.
